CLAIM

I claim the ornamental design for an upper member of an advertising carrying body for use on a filler gun, as shown and described.

DESCRIPTION

FIG. 1 is a top, front perspective view from one side of the upper member of the advertising carrying body.

FIG. 2 is a top, rear perspective view from the other side of the upper member of the advertising carrying body.

FIG. 3 is a bottom, rear perspective view from said one side of the upper member.

FIG. 4 is a bottom, front perspective view of the upper member; and,

FIG. 5 is a top, front perspective view of the upper member.
